JIGGING APPARATUS

Edmond Harvengt, Moustier-sur-Sambre, Belgium, assignor to Link-Belt Company, Chicago, Ill., a corporation of Illinois

Application January 22, 1953, Serial No. 332,637

21 Claims. (Cl. 209—455)

This invention relates to improvements in washer boxes, jigs, or similar apparatus, in which a piston, or the like, is employed to produce liquid impulses upwardly through a bed of material supported on a screen in order to effect a classification of the material particles according to their individual densities or settling rates.

This application is a continuation-in-part of my co-pending application, Serial No. 739,379, filed April 4, 1947, and now abandoned for Jigging Method and Apparatus.

The basic principle of jigging materials to effect classification of the different particles according to their individual densities or settling rates has been known for many years and need not be discussed in detail at this time. It, also, is well-known that the impulse, or material bed opening or lifting, strokes of the liquid actuating piston are responsible for the major portion of the classifying action that is performed on the material being treated while the return, or suction, strokes of the piston, which cause the particles of the opened up or lifted bed to be forcibly pulled downwardly toward the supporting screen at a false or unnatural settling rate, at least partially destroy the accurate classification of the material particles that was effected by the impulse producing strokes.

Prior attempts to overcome the undesirable effect of the suction strokes of the piston by the introduction of water into the hutch portion of the washer box or jig have not been entirely successful because they have failed to recognize the importance of accurately measuring the water introduced into the hutch so that the amount forming each charge will bear the relationship to the volumetric displacement of the piston that is essential to effect the desired classifying action.

For example, it will be recognized that each impulse producing stroke of the piston, if the length of the strokes is maintained constant, will effect the displacement of a constant volume of liquid upwardly through the material bed supporting screen, and that the extent to which such constant volume liquid impulses will open up or lift the bed of material will depend primarily on the kind of material being treated and the characteristics of the bed as a whole; that is, the average, and range of, settling or density rates of the material particles, the thickness of the material bed, and the like. Therefore, it should be appreciated that the most efficient classifying of different kinds of materials, and of beds of materials having different classifications, can be effected only if an accurate control is exercised over the relationship between the bed opening or lifting effect of the impulse producing strokes of the piston and the extent to which the effect of the suction strokes of the piston is applied to the bed.

To further illustrate, under certain operating conditions, the most efficient classification will be accomplished by exactly counterbalancing the effect of the suction strokes, with the result that the particles of the opened up or lifted bed will be permitted to settle entirely in

2

accordance with their individual density or settling rates. Other operating conditions will require the effect of the suction strokes to be underbalanced; that is, not completely counterbalanced, with the result that the rates at which the individual particles of the opened up or lifted bed will actually settle will exceed their normal settling rates. Still other operating conditions will require the effect of the suction strokes to be overbalanced; that is, more than counterbalanced, with the result that the rates at which the individual particles will actually settle will be slower than their normal settling rates.

To exactly counterbalance the effect of the suction, the amount of liquid delivered to the hutch during each suction stroke of the piston must exactly equal the volumetric displacement of the piston. When the effect of the suction is underbalanced, the amount of liquid delivered to the hutch is less than the displacement of the piston, and when the effect of the suction is overbalanced, the amount of liquid delivered to the hutch exceeds the displacement of the piston. It is quite obvious, therefore, that the most efficient classification of different kinds of materials, and of beds having different characteristics, can be obtained only if the amount of liquid delivered to the hutch during each suction stroke bears a very accurate, and the essential, relationship to the volumetric displacement of the piston, and if such relationship can be varied or changed at the will of the operator to meet the requirements of the different operating conditions that may be encountered.

It should be apparent that these requirements are not met by the prior attempts that have been made to solve the suction problem. In one such general type, the suction counterbalancing charges of liquid, that are delivered directly to the hutch, are obtained from a water supply line in which the pressure may vary, and are controlled only by an intermittently actuated valve. In the other general type, the charges of liquid are measured by the impulse and suction producing piston, and, for that reason, the amount of liquid forming each charge cannot be varied or changed at the will of the operator, relative to the volumetric displacement of such piston.

The primary object of this invention is to provide a washer box, jig, or similar apparatus, in which the effect of the suction producing strokes of the liquid actuating piston can be either exactly counterbalanced, underbalanced to any desired extent, or overbalanced to any desired extent, at the will of the operator, by the introduction to the hutch of liquid charges that bear a very accurate, and the essential, relationship to the volumetric displacement of such piston.

A more specific object of the invention is to control the effect of the suction producing strokes, in washer boxes, jigs, or similar apparatus, by delivering to the hutch charges of liquid which are individually, accurately measured as a result of being developed in a chamber, the volumetric capacity of which can be varied to make possible the delivery of charges which bear any desired relationship to the volumetric displacement of the piston that is employed for producing the suction strokes.

Still another object of the invention is to provide material classifying apparatus which involves two washer boxes, or jigs, connected to operate in series, which have their respective liquid impulse producing pistons driven by a common shaft at an angular relationship of 180°, and in which a suction balancing charge of liquid from a pressure source is delivered to a chamber individual to, and bounded on one side by, each piston during its liquid impulse producing stroke so that the force of each charge of liquid that is applied to either piston will counterbalance, or lessen, to a very substantial extent, the amount of force that must be applied by said common drive shaft to the other piston to move it

through its simultaneously enacted suction producing stroke, with the result that the power required to operate such a two-unit assembly will be very substantially reduced.

Other objects and advantages of the invention will be apparent during the course of the following description.

In the accompanying drawings forming a part of this specification and in which like numerals are employed to designate like parts throughout the same,

Figure 1 is a vertical sectional view of a two-unit washer box or jig assembly, embodying the invention, Figure 2 is a vertical sectional view taken on lines 2-2 of Fig. 1,

Figure 3 is a vertical sectional view taken on lines 3-3 of Fig. 1,

Figure 4 is a vertical sectional view taken on lines 4-4 of Fig. 2,

Figure 5 is a vertical sectional view of a modified form of wash box or jig unit, and

Figure 6 is a similar view to Fig. 5, and illustrates a further modified form of unit.

In the drawings, wherein for the purpose of illustration are shown the preferred embodiments of this invention, and first particularly referring to Figs. 1 to 4, inclusive, there is illustrated a two-unit washer box, or jig, assembly, in which the two boxes 10 are connected end-to-end so they will operate in series; that is, with the material to be treated being delivered to the receiving end of one of the boxes by means of the trough 11 while the end product will be discharged from the outer end of the second box by the trough 12.

By particularly inspecting Figs. 2 and 3, it will be seen that each one of the boxes is provided with a longitudinally extending partition 13 which divides the upper portion into a screen section 14 and a piston section 15. These two sections extend the full length of each one of the boxes.

In each screen section 14 there is positioned a material bed supporting screen 16 of any desired mesh size. The material to be treated, which is delivered by the trough 11, is deposited on the receiving end of the screen 16 of the left-hand unit, as viewed in Fig. 1, and this material advances longitudinally of the box as it is being classified. In passing from the first box to the second box, the material passes over the dividing plate, or weir, 17, which may be adjustable in height to determine the depth of the material bed. From the outer end of the second box, the material is discharged through the opening 18 into the trough 12.

The section 15 of each one of the boxes is provided with a piston 19 that is intended to be reciprocated through strokes of a desired but constant length by suitable mechanism which will be described at a later point. Each one of these pistons 19 is sealed or packed at its periphery by means of a flexible membrane 20. It will be appreciated that other forms of sealing or packing means may be employed. The top of each one of the piston sections is closed by a wall 21 which cooperates with the associated piston 19 to form a liquid measuring chamber 22. Fig. 1 illustrates the two chambers as being isolated from each other by means of the common intermediate wall 23 of the two boxes. Each one of the two chambers 22 is provided with a breather pipe 24 which prevents the trapping of air in the chamber.

The portion 25 of each one of the two boxes that is located below the screen and piston sections 14 and 15, respectively, constitutes the hutch of the box, and, as is clearly illustrated in Figs. 2 and 3, the hutch is in constant, open communication with the screen section 14 and the piston section 15. Consequently, when the two boxes are provided with the desired liquid, such as water, to the proper level, the reciprocating movements of the pistons 19 will produce pulsations in the water which will be transmitted to the material supported on the screens 16 of the boxes. In other words, when each piston

moves downwardly, it will produce a liquid impulse that will pass from its piston section 15 through the hutch 25 to the screen section 14 and upwardly through the screen 16 and the bed of material that is supported by said screen. The return movements of the pistons, commonly referred to as the suction strokes, would effect a reverse movement of the liquid, to the extent of the volumetric displacement of the pistons, downwardly through the beds of material and the screens 16 if the effects of the suction strokes were not counteracted.

A drive shaft 26, common to both of the units, is supported by suitable bearings 27 mounted on appropriate bracket arms 28 so that the shaft is arranged to centrally overlie the two piston sections 15. This shaft has 15 suitably keyed thereto the two eccentric drive units 29 which are employed for effecting reciprocation of the pistons through the jointed connection rods 30. It will be noted by considering Fig. 1 that the eccentrics 29 are positioned on the common drive shaft 26 so the pistons 20 will be reciprocated relative to each other at an angular relationship of 180°. The shaft 26 is driven at the desired speed by the pulley or sprocket wheel 31 over which may be trained a desired flexible drive member driven by any suitable motor, not shown.

25 The liquid chamber 22 for each one of the washer box units receives a very accurately measured charge of liquid during each downward, or impulse producing, stroke of its piston 19 and this charge of liquid is transferred from the chamber 22 to the hutch 25 during 30 each return, or suction, stroke of the piston. The mechanism employed for effecting this delivery and transfer of liquid charges now will be described.

Figs. 2 and 4 disclose the valve housings 32 which are provided for the two boxes. These two housings are 35 interconnected by the manifold pipe 33 to assure uniform flow of liquid to both of the housings. Each housing is provided with a flanged inlet 34 connected to a liquid supply line 35, one of which is illustrated in Fig. 2. These supply lines are to be connected to a suitable source 40 of the desired liquid, not shown, which may take the form of either an elevated storage tank or a water main. In either event, the liquid delivered to the valve housings 32 is under a substantial pressure.

Each one of the valve housings 32 is provided with a first liquid outlet 36 connected to the associated liquid chamber 22. A second liquid outlet 37 connects each one of the valve housings to the hutch 25 below its associated piston 19. Each valve housing 32 has rotatably positioned therein a valve body 38 mounted on a shaft section 39. The two shaft sections are supported by their respective bearings 40 while the adjacent ends are connected by the coupling 41. A drive pulley 42 for both of the shaft sections has trained thereover the flexible drive element 43 which in turn is trained over the pulley 44 mounted on the common drive shaft 26. An appropriate take-up mechanism 45 is employed for tensioning the drive element 43 and for training the two runs of this element so that they will not engage the adjacent wall of the box structure.

55 60 It will be noted, by inspecting Fig. 4, that the valve bodies 38 are arranged at right angles to each other so that while one side of one of the valves is closing the entrance end of the first liquid outlet 36, see Fig. 2, one of the ends of the other valve will be positioned to close its liquid outlet 37. The pulleys 42 and 44 are so proportioned that the shafts 39 for the two valve bodies will make one complete revolution for every two revolutions of the drive shaft 26.

65 70 The valve bodies 38 are so shaped and are so rotated in timed relation to the strokes of their pistons 19 that liquid under pressure will be delivered to each liquid chamber 22 during each liquid impulse producing movement of the associated piston 19 while liquid will flow from said chamber 22 into the hutch 25 during each return, or suction, stroke of the piston. This reverse flow of liquid

will occur during each half-revolution of the valve body 38.

Because the liquid actuating pistons 19 of the two boxes are driven by a common shaft at an angle of 180° relative to each other, and because liquid under pressure is delivered to each chamber 22 during each impulse producing stroke of its associated piston 19, the admitted liquid charges will materially assist in driving the pistons through such strokes and in reducing the amount of power that must be applied to the common shaft 26 to effect the return, or suction, strokes of the pistons. Additionally, because a charge of liquid is delivered to the hutch of each box during the suction, or return, stroke of its associated piston, the amount of power or force that must be exerted to move each piston through such stroke is materially reduced. Consequently, if the liquid that is admitted to the chambers 22 during the impulse producing strokes of their associated pistons 19, is at least at a pressure of from 75 pounds to 100 pounds per square inch, very little power is required to drive this two-unit type of washer box or jig.

It is very desirable, in handling different kinds of materials, and material beds having different characteristics, to be able to very accurately control or regulate the amount of liquid charge that is delivered to each hutch 25 during each return, or suction, stroke of its piston 19 so that suction action or effect on the material bed can be accurately regulated, and, in fact, changed at the will of the operator. These changes become necessary to permit the suction action to be either exactly counterbalanced, underbalanced to any desired extent, or overbalanced to any desired extent. The mechanism employed for accurately regulating or controlling the amount of liquid delivered to each one of the chambers 22, during the impulse producing strokes of its associated piston 19, now will be explained.

The top wall 21 of each one of the chambers 22 has an opening formed therein in which is mounted a cylinder structure 46. Positioned to reciprocate in each cylinder structure is a plunger 47 which has a joined rod 48 connected thereto. The upper end of each connecting rod is suitably, pivotally attached to a crank pin 49 carried by a mounting plate 50 that is adjustably connected to a drive plate 51 by means of the slots and bolts 52 and 53. In other words, the off-center, or throw, of the pins 49 can be changed by adjusting the relative positions of the two plates 50 and 51.

By considering Figs. 1 and 2, it will be seen that the plungers 47 reciprocate in phase relation with their respective pistons 19 so the plungers will move into the chambers 22 while the associated pistons 19 are moving downwardly through their impulse producing strokes. The plungers 47, therefore, reduce the capacities of their respective chambers 22 during the periods when liquid charges are delivered to these chambers. By changing the off-center positions of the crank pins 49, the plungers 47 may be caused to move different distances into the associated chambers 22, and thereby regulate or change the capacities of these chambers.

Fig. 5 illustrates diagrammatically a modified form of washer box or jig assembly which includes the box 54 that has its upper portion divided by the partition 55 into a screen section 56 and a piston section 57. The two sections 56 and 57, below the bottom edge of the partition 55, are constantly connected by the hutch 58. A suitable screen 59 is mounted in the screen section 56 to support the bed of material that is to be classified.

The piston section 57 has mounted therein a reciprocating piston 60 operated by the rod 61 which is connected by the eccentric 62 to the drive shaft 63. The piston has formed therein a liquid outlet 64 controlled by a valve 65 resiliently urged toward its closed position by the spring 66. The valve rod 67 is connected to one arm 68 of a pivoted lever that has its other arm 69 forked to straddle the piston rod 61 and engage the actuating pin 70. Be-

cause of this mechanical connection, the valve 65 is forced from its seat, against the pressure of the spring 66, each time the piston 60 is moved upwardly, or through its suction stroke.

The upper portion of the piston section 57 has mounted therein a plunger 71 that cooperates with the piston to form a liquid chamber 72. The plunger is connected to a tubular rod 71a which has its upper end adjustably connected to an eccentric 73 by means of the threaded pin 74, the apertured ear 75 and the locknuts 76. The eccentric 73 is suitably mounted on the shaft 77 that is driven at a one-to-one speed ratio from the shaft 63 by means of the sprocket and chain drive connection 78.

It will be appreciated the plunger 71 will be reciprocated in phase relation with the piston 60 so the plunger will move downwardly as the piston moves through its liquid impulse producing stroke and will move upwardly with the piston as the latter moves through its return, or suction producing, stroke. By adjusting the connection 74-75-76, the capacity of the chamber 72, formed between the piston 60 and the plunger 71, may be varied to take care of different operating conditions.

Liquid from a suitable source of supply, maintained under any desired pressure, is supplied to the chamber 72 by means of the pipe line 79. The piston 60 is illustrated in its lowermost position, or after it has completed its impulse producing stroke. When in this position, the lower end of the supply line 79 is open so that a charge of liquid will be delivered to the chamber 72. The upward movement of the piston 60, during its return, or suction, stroke will cause the discharge end of the pipe line 79 to be closed and to remain closed until the piston again moves downwardly through an impulse producing stroke.

From the above description, it will be seen that liquid will be delivered to the chamber 72 during each impulse producing stroke of the piston 60 and this charge of liquid will be delivered to the hutch 58 through the outlet 64 as the piston 60 moves through its next return, or suction, stroke. Because the capacity of the chamber 72 can be regulated or changed by adjusting the position of the plunger 71 relative to the piston, the charges of liquid successively delivered to the chamber 72 may be very accurately measured relative to the volumetric displacement of the piston, with the result that the suction action or effect of the piston, on the bed of material supported by the screen 59, may be very accurately regulated to either exactly counterbalance the suction or to effect an underbalance or an overbalance of said suction.

Fig. 6 diagrammatically illustrates a further modified form of washing box or jig which includes the box 79 that has its upper portion divided by the partition 80 into a screen section 81 and a piston section 82. A hutch 83 is formed in the box below the two sections 81 and 82.

The screen section 81 has suitably mounted therein a screen 83 for supporting the bed of materials being classified in the box.

The piston section 82 has mounted therein a piston 84 reciprocated by means of the piston rod 85 passing through the cover 86 which closes the upper end of the piston section 82 and cooperates with the piston 84 to form a liquid chamber 87. The piston rod 85 is pivotally connected to the rocker arm 88 which is pivotally supported at 89 and is connected at its opposite end by the rod 90 to the eccentric 91 driven by the shaft 92.

During each impulse producing stroke of the piston 84, a carefully measured charge of liquid is delivered to the chamber 87. This charge is directed into the hutch 83 during each return, or suction, stroke of the piston 84. The mechanism employed for effecting the delivery and transfer of these successive liquid charges in phase relation to the reciprocation of the piston 84 now will be described.

The pipe line 93 is intended to be connected at its upper end to any suitable source of liquid under pressure and at its lower end to a valve housing 94 formed with

a first liquid outlet 95 and a second liquid outlet 96. The outlet 95 connects the valve housing with the chamber 87 while the outlet 96 connects the valve housing with the hutch 83.

Positioned within the housing 94 is a reciprocating valve 97 that is moved through strokes of desired but adjustable lengths by means of the joined valve rod 98 which is adjustably connected at its lower end to the crank arm 99 suitably fastened to the drive shaft 100. The shaft 100 is driven at a one-to-one ratio from the piston reciprocating shaft 92 by means of the flexible drive connection 101.

During each downward, or impulse producing, stroke of the piston 84, the valve 87 is moved downwardly to uncover the liquid outlet 95 so a charge of fluid will flow from the supply pipe 93 to the chamber 87. As the piston 84 moves through its return, or suction, stroke, the valve 97 is moved upwardly to establish communication between the two outlets 95 and 96 so the charge of liquid previously delivered to the chamber 87 will pass through the valve housing 94 into the hutch 83 to counteract the effect or action of the suction stroke of the piston.

By adjusting the point of connection between the lower end of the piston-operating rod 98 and the crank arm 99, it will be appreciated that the length of the strokes of the valve may be changed. This change will bring about the delivery of a different quantity of liquid to the chamber 87 during each downward, or impulse producing, stroke of the piston 84. Consequently, the extent to which the suction action or effect of the piston on the material supported by the screen 83 may be varied to cause the suction action to be either exactly counterbalanced, underbalanced to any desired extent, or overbalanced to the desired extent.

It is to be understood that the forms of this invention herewith shown and described are to be taken as preferred examples of the same and that various changes in the shape, size and arrangement of parts may be resorted to without departing from the spirit of the invention or the scope of the subjoined claims.

Having thus described the invention, I claim:

1. A washer box, jig, or like apparatus, comprising a box having a partition dividing its upper portion into a piston housing section and a screen section, the portion of the box below the partition and said sections forming a hutch in continuous open communication with said sections, a screen in the screen section for supporting material to be classified by liquid impulses passing from the piston housing section through the hutch to the screen section, a piston reciprocating in its housing section to produce said liquid impulses, means including a rotatable shaft for reciprocating said piston through strokes of constant length, means for supplying liquid from an external source, means forming a chamber to alternately receive liquid from said supply means and to discharge liquid into the said hutch, valvular means for directing the alternate flow of liquid into and from said chamber, means directly connecting the rotatable shaft of the piston reciprocating means and said liquid flow directing means for positively actuating said latter means in phase relation with the strokes of the piston to bring about the flow of liquid into said chamber during each impulse producing stroke of the piston and the flow of liquid from the chamber into the hutch during each return stroke of the piston, means for controlling the amount of liquid permitted to flow into and from said chamber, means directly connecting the rotatable shaft of the piston reciprocating means to said liquid flow controlling means for actuating said latter means in phase relation with the strokes of said piston, and independently adjustable means included as a part of the aforesaid directly connecting means of the liquid flow controlling means for adjusting the action of the latter means to change the

amount of liquid flowing into and from the chamber while the strokes of the piston remain at their aforesaid constant length.

2. A washer box, jig, or like apparatus as specified in claim 1 further characterized by the means forming the liquid chamber comprising the portion of the piston housing section above the reciprocating piston.

3. A washer box, jig, or like apparatus as specified in claim 2 further characterized by the means for controlling the amount of liquid permitted to flow into and from said chamber comprising a plunger positioned to reciprocate axially of the chamber in phase relation with the piston to reduce the capacity of the chamber while the liquid is flowing into the chamber.

15 4. A washer box, jig, or like apparatus as specified in claim 3 further characterized by the means for adjusting the action of the liquid flow controlling means comprising an adjustable connection in the means for actuating the plunger to vary the length of the strokes of the plunger relative to the constant length of the strokes of the piston.

5 5. A washer box, jig, or like apparatus as specified in claim 4 further characterized by the valvular means for directing the alternate flow of liquid into and from the chamber cooperating with a liquid inlet for the chamber connected to the means for supplying liquid from an external source, a liquid outlet for the chamber connected to the hutch, and a valve member operating in phase relation with the piston for alternately opening and closing said liquid inlet and said liquid outlet in reverse order.

20 6. A washer box, jig, or like apparatus as specified in claim 2 further characterized by the valvular means for directing the alternate flow of liquid into and from the chamber cooperating with a valve housing positioned outside the box and connected to the liquid supplying means, a first liquid outlet for the valve housing connected to said chamber, a second liquid outlet for the valve housing connected to the hutch, and a rotatable valve member in the valve housing for alternately directing liquid from said housing into the chamber through the first liquid outlet and from said chamber to the hutch through said first and second liquid outlets and the valve housing.

25 7. A washer box, jig, or like apparatus, comprising a box, a piston housing arranged with its axis substantially vertical, a piston reciprocating in the piston housing, means including a rotatable shaft for reciprocating said piston, a screen in the box for supporting materials to be treated, the housing above the piston acting as a chamber for liquid, means for supplying liquid from an external source to said chamber, means for controlling the flow of liquid from said external source into said chamber and from said chamber into the portion of the box located below the screen, said liquid control means comprising a valve housing, a liquid inlet for the valve housing connected to the liquid supply means, a liquid outlet for the valve housing connected to said chamber, a liquid outlet for the valve housing connected to the box, a single actuatable valve member in the valve housing for alternately connecting said liquid inlet with the liquid outlet to said chamber and the liquid outlet for said chamber with the liquid outlet to the box, and mechanism operatively connected with the reciprocating means for the piston of the box for actuating said valve, said mechanism comprising a rotatable shaft operatively connected to the valve member, and a drive connection between the rotatable shaft of the piston reciprocating means and the shaft for the valve member.

30 8. A washer box, jig, or like apparatus, comprising a box, a piston housing arranged with its axis substantially vertical, a piston reciprocating in the piston housing, means for reciprocating said piston, a screen in the box for supporting materials to be treated, the housing above the piston acting as a chamber for liquid, means for supplying liquid from an external source to said chamber,

means for controlling the flow of liquid from said external source into said chamber and from said chamber into the portion of the box located below the screen, said liquid control means comprising a valve housing, a liquid inlet for the valve housing connected to the liquid supply means, a liquid outlet for the valve housing connected to said chamber, a liquid outlet for the valve housing connected to the box, a reciprocating valve in the valve housing for alternately connecting said liquid inlet with the liquid outlet to said chamber and the liquid outlet for said chamber with the liquid outlet for the box, an operating mechanism for said reciprocating valve operatively connected with the reciprocating means for the piston and means for adjusting said mechanism to modify the reciprocating movement of the valve.

9. A washer box, jig, or like apparatus, comprising a box, a piston housing arranged with its axis substantially vertical, a piston reciprocating in the piston housing, means for reciprocating said piston, a screen in the box for supporting materials to be treated, the housing above the piston acting as a chamber for liquid, means for supplying liquid from an external source to said chamber, means for controlling the flow of liquid from said external source into said chamber and from said chamber into the portion of the box located below the screen, said liquid control means comprising a valve housing, a liquid inlet for the valve housing connected to the liquid supply means, a liquid outlet for the valve housing connected to said chamber, a liquid outlet for the valve housing connected to the box, a reciprocating valve in the valve housing for alternately connecting said liquid inlet with the liquid outlet to said chamber and the liquid outlet for the box, an operating mechanism for said reciprocating valve, and an operative connection between said mechanism and the reciprocating means for the piston, said operative connection enabling changes to be made in the phase relation between the reciprocating movements of the piston and those of the valve.

10. A washer box, jig, or like apparatus, comprising a box, a piston housing arranged with its axis substantially vertical, a piston reciprocating in the piston housing, means for reciprocating said piston, a screen in the box for supporting materials to be treated, the housing above the piston acting as a chamber for liquid, means for supplying liquid from an external source to said chamber, means for controlling the flow of liquid from said external source into said chamber and from said chamber into the portion of the box located below the screen, said liquid control means comprising a valve housing, a liquid inlet for the valve housing connected to the liquid supplying means, a liquid outlet for the valve housing connected to said chamber, a liquid outlet for the valve housing connected to the box, and a rotatable valve in the valve housing for alternately connecting said liquid inlet with the outlet to said chamber and the outlet for said chamber with the outlet for the box, and means operatively connected to said piston reciprocated means for moving said valve substantially in phase relation with the strokes of said piston, said last mentioned means comprising a shaft for rotating the valve, and a drive connection between the piston reciprocating means and the valve shaft.

11. A washer box, jig, or like apparatus, comprising a box, a piston housing arranged with its axis substantially vertical, a piston reciprocating in the piston housing, means for reciprocating said piston, a screen in the box for supporting materials to be treated, the housing above the piston acting as a chamber for liquid, means for changing the capacity of said liquid chamber, means for supplying liquid from an external source to said chamber, means for controlling the flow of liquid from said external source into said chamber and from said chamber into the portion of the box located below the screen, said liquid control means comprising a valve housing, a liquid inlet for the valve housing connected to the liquid sup-

plying means, a liquid outlet for the valve housing connected to said chamber, a liquid outlet for the valve housing connected to the box, and a rotatable valve in the valve housing for alternately connecting said liquid inlet with the outlet to said chamber and the outlet for said chamber with the outlet for the box, and means operatively connected to said piston reciprocated means for moving said valve substantially in phase relation with the strokes of said piston, said last mentioned means comprising a rotatable shaft for the valve, and a drive connection between the piston reciprocating means and the valve shaft.

12. A washer box, jig, or like apparatus, comprising a box, a piston housing arranged with its axis substantially vertical, a piston reciprocating in the piston housing, means for reciprocating said piston, a screen in the box for supporting materials to be treated, the housing above the piston acting as a chamber for liquid, a plunger reciprocating in the liquid chamber to control the capacity of said chamber, means operatively connected to said piston reciprocating means for moving the plunger in phase relation with the reciprocations of said piston, means for adjusting said connecting means to change the length of the strokes of the plunger relative to the length of the strokes of the piston, means for supplying liquid from an external source to said chamber, means for controlling the flow of liquid from said external source into said chamber and from said chamber into the portion of the box located below the screen, said liquid control means comprising a valve housing, a liquid inlet for the valve housing connected to the liquid supplying means, a liquid outlet for the valve housing connected to said chamber, a liquid outlet for the valve housing connected to the box, and a rotatable valve in the valve housing for alternately connecting said liquid inlet with the outlet to said chamber and the outlet for said chamber with the outlet for the box, and means operatively connected to said piston reciprocated means for moving said valve substantially in phase relation with the strokes of said piston, said last mentioned means comprising a rotatable shaft for the valve, and a drive connection between the piston reciprocating means and the valve shaft.

13. A washer box, jig, or like apparatus, comprising a box, a piston housing in the box, a piston reciprocated in the housing, means for reciprocating said piston, a screen in the box for supporting materials to be treated, a chamber in said box formed as an extension of the piston housing, a plunger in said box having a working face forming a wall of said chamber, means for supplying liquid to said chamber, means for discharging liquid from said chamber into said box, means under the control of the piston reciprocating means for controlling the supply of liquid to said chamber and the liquid discharge from said chamber into said box, and means for controlling the position of the plunger in said housing.

14. A washer box, jig, or like apparatus, comprising a box, a piston housing in the box, a piston reciprocated in the housing, means for reciprocating said piston, a screen in the box for supporting materials to be treated, a chamber in said box formed as an extension of the piston housing, a plunger in said box having a working face forming a wall of said chamber, means for supplying liquid to said chamber, means for discharging liquid from said chamber into said box, means under the control of the piston reciprocating means for controlling the supply of liquid to said chamber and the liquid discharge from said chamber into said box, and means for reciprocating the plunger to modify the volume of said chamber.

15. A washer box, jig, or like apparatus, comprising a box, a piston housing in the box, a piston reciprocated in the housing, means for reciprocating said piston, a screen in the box for supporting materials to be treated, a chamber in said box formed as an extension of the piston housing, a plunger in said box having a working face forming a wall of said chamber, means for supplying

liquid to said chamber, means for discharging liquid from said chamber into said box, means under the control of the piston reciprocating means for controlling the supply and the discharge of the liquid into and from said chamber, and means for reciprocating said plunger in said housing, said latter reciprocating means being adjustable to vary the length of the strokes of the plunger.

16. A washer box, jig, or like apparatus, comprising a box, a piston housing in the box, a piston reciprocated in the housing, means for reciprocating said piston, a screen in the box for supporting materials to be treated, a chamber in said box formed as an extension of the piston housing, a plunger in said box having a working face forming a wall of said chamber, means for supplying liquid to said chamber, means for discharging liquid from said chamber into said box, valve means under the control of the piston reciprocating means for controlling the supply and the discharge of the liquid into and from said chamber, said valve means including a rotatable member, and adjustable means for reciprocating said plunger.

17. A washer box, jig, or like apparatus, comprising a box, a piston housing in the box, a piston reciprocated in the housing, means for reciprocating said piston, a screen in the box for supporting materials to be treated, a chamber in said box formed as an extension of the piston housing, a plunger in said box having a working face forming a wall of said chamber, said working face having a substantially reduced area as compared with that of the piston, means for supplying liquid to said chamber, means for discharging liquid from said chamber into said box, valve means under the control of the piston reciprocating means for controlling the supply and the discharge of the liquid into and from said chamber, said valve means including a rotatable member, and adjustable means for varying the length of the strokes of the plunger.

18. A washer box, jig, or like apparatus, comprising a pair of joined boxes, each box having a partition dividing its upper portion into a piston section and a screen section with the portion of the box below the partition and said sections forming a hutch, a screen in each screen section for supporting material to be classified by liquid impulses developed in the piston housing section, a piston reciprocating in each piston housing section to produce said material classifying liquid impulses, a driven shaft common to both boxes, drive connections from said shaft for reciprocating the two pistons at a 180° angular relationship, means for supplying liquid under pressure from an external source, means forming the portion of each

5 piston housing section above its piston into a chamber to alternately receive liquid from said supply means and to discharge liquid into the hutch of its box, valve means associated with each box for directing the alternate flow of liquid into and from its chamber, and a drive connection from said common shaft to each valve means for actuating the valve means in phase relation with the strokes of its piston to bring about the flow of said liquid under pressure into the chamber above the piston during each impulse producing stroke of the piston and the flow of liquid from the chamber into the hutch below the piston during each return stroke of the piston.

10 19. A washer box, jig, or like apparatus as specified in claim 18 further characterized by means associated with each box for controlling the amount of liquid permitted to flow into and from its chamber comprising a plunger positioned to reciprocate into and out of the chamber in phase relation with the piston to reduce the capacity of the chamber during each impulse producing stroke of the piston.

15 20. A washer box, jig, or like apparatus as specified in claim 18 further characterized by a plunger for each box positioned to reciprocate into and out of the chamber, a drive connection from said common shaft for each 25 plunger to reciprocate the plunger in phase relation with its piston to reduce the capacity of the chamber during each impulse producing stroke of the piston, and means for adjusting each of said drive connections to change the length of the strokes of the plunger.

20 21. A washer box, jig, or like apparatus as specified in claim 18 further characterized by the valve means for directing the alternate flow of liquid into and from its chamber comprising a housing positioned outside the box and connected to the liquid supplying means, a first liquid 30 outlet for the housing connected to the chamber, a second liquid outlet for the housing connected to the hutch, and a rotatable valve in the housing for alternately directing liquid from said housing into the chamber through the first liquid outlet and from said chamber into the hutch 35 through said first and second liquid outlets and said housing.
